UNITED STATES PATENT OFFICE.

HARRY E. CAMPBELL, OF NEW YORK, N. Y., ASSIGNOR TO CAMPBELL METAL WINDOW CORPORATION, OF BALTIMORE, MARYLAND, A CORPORATION OF MARYLAND.

SLIDABLE WINDOW SASH.

Application filed November 30, 1921. Serial No. 518,758.

To all whom it may concern:

Be it known that I, HARRY E. CAMPBELL, a citizen of the United States, residing at New York, in the county of New York and State of New York, have invented a certain new and useful Improvement in Slidable Window Sashes, of which the following is a specification.

This invention relates to windows of the type in which the jamb is provided with openings in its inner face and with a partition extending across such openings and the sash is provided with plates adapted to go through such openings and contact with such partition. A window of this type is described in my United States Patent No. 1,241,090 dated Sept. 25, 1917.

The adjustment of transverse movement has always been a great problem, particularly with metal sashes, and by my present invention I provide a simple method of making such adjustment within the jamb where the adjusting means will not be visible after the window is completely assembled. The manner in which my invention may be carried out will be readily apparent from the examples illustrated in this specification.

In the accompanying drawing—

Fig. 1 shows in elevation a portion of a sash frame and extension plate, and of a partition or fixed plate against which the vertical edge of said extension plate bears. Fig. 2 shows a modification of the manner of producing projections on the bearing edge of the extension plate.

Similar numbers of reference indicate like parts.

1 is a portion of a sash frame which carries the usual glass pane 2. 3 is the extension plate of metal secured on a side rail of said frame. 4 is a vertical fixed plate or partition within the jam, upon which said extension plate bears. In order to ensure contact of the extension plate against the fixed jamb plate, I form integrally with and on the edge of said extension plate, elastic protrusions which bear upon the jamb plate. In Fig. 1 said protrusions are

the tongues 5 formed by cutting the metal 50 at said edge and bending the same outwardly to bear upon the fixed plate. Said tongues are preferably bent in curved shape, so that their convexities make contact with the fixed plate. 55

Instead of forming tongues in the manner described, I may cut slots 6 near the edge of the extension plate and bend the metal between the slots and the edge so as to project outwardly, as shown at 7, the 60 convexity produced as before bearing against the jamb plate. As many tongues 5 or projections 7 may be made as desired along the edge of the extension plate and should protrude sufficiently to be somewhat 65 compressed against their own elasticity when the sash is in place in the frame. As the extent of protrusion is easily adjusted by simply bending tongue or projection more or less outwardly, it follows that any slight 70 variations in the width of the sash which would result in its being too loose in its frame is thus compensated for.

I claim:—

In a window of the type in which the jamb is provided with openings in its inner face, the combination of a jamb member adapted to stand behind the plane of the inner jamb wall, a sash having plates substantially the height of the sash adapted 80 to extend into each jamb, slots near the edges of the plates and contact portions of the plates partially separated from the plates by such slots bent out to contact with said jamb member, said contact portions 85 being of such thickness as to permit of bending by a manual operation to give a transverse adjustment to the sash, and at the same time to be stiff enough to form an elastic contact between the sash and the 90 jamb member.

In testimony whereof I have affixed my signature in presence of two witnesses.

HARRY E. CAMPBELL.
